US0D1099252S

(12) **United States Design Patent** (10) **Patent No.:** **US D1,099,252 S**
(45) **Date of Patent:** **** Oct. 21, 2025**

(54) **FIREARM**

(71) Applicant: **STACCATO 2011, LLC**, Georgetown, TX (US)

(72) Inventors: **Jeffery Hildner**, Belton, TX (US); **Nathan Horvath**, Austin, TX (US); **Cullen Fravel**, Killeen, TX (US); **Dustin Turner**, Georgetown, TX (US); **Christopher Schirmer**, Georgetown, TX (US); **Anthony Clark, II**, Round Rock, TX (US); **Kristin Marlow**, Austin, TX (US); **Justin Honea**, Spicewood, TX (US); **Jeffrey M. D'Alessio**, Rockwall, TX (US); **Paul Smith**, Bozeman, MT (US)

(73) Assignee: **Staccato 2011, LLC**, Florence, TX (US)

(**) Term: **15 Years**

(21) Appl. No.: **29/857,624**

(22) Filed: **Oct. 24, 2022**

(51) LOC (15) Cl. **22-01**

(52) U.S. Cl. ..... **USPC D22/104**

(57) **CLAIM**

The ornamental design for a firearm, as shown and described.

DESCRIPTION

FIG. 1 is a front perspective view of a firearm;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines and the unshaded areas adjacent to them depict portions of a firearm that form no part of the claimed design.

1 Claim, 7 Drawing Sheets
